UNITED STATES PATENT OFFICE.

HENRY LECHTENBERG, OF QUINCY, ILLINOIS, ASSIGNOR TO CENTRAL IRON WORKS, OF QUINCY, ILLINOIS, A CORPORATION.

DUST-ARRESTER.

No. 870,830.

Specification of Letters Patent.

Patented Nov. 12, 1907.

Application filed October 25, 1906. Serial No. 340,476.

To all whom it may concern:

Be it known that I, HENRY LECHTENBERG, a citizen of the United States of America, residing in Quincy, in the county of Adams and State of Illinois, have invented certain new and useful Improvements in Dust Arresters, of which the following is a full, clear, and exact description, reference being had to the accompanying drawings, forming part of this specification.

My invention relates to a dust arrester more particularly intended for use in collecting the dust produced in tumbling mills and by polishing wheels and emery wheels.

Figure I is a vertical longitudinal section taken through my dust arrester and illustrating the screen members within the arrester casing partly in elevation and partly in section. Fig. II is an enlarged view of a portion of one of the screen members partly broken away, the valve box at the rear end of the arrester and the hammer mechanism by which the screen members are jarred to discharge accumulations of dust gathered on the exterior surfaces. Fig. III is an enlarged cross section taken through one of the screen members and showing one of the hammers in elevation. Fig. IV is an elevation of the door at the rear end of the arrester.

25 1 designates the casing of my dust arrester which is provided at its bottom with a hopper 2 and contains a dust receiving chamber 3. The dust to be gathered in the arrester enters the dust receiving chamber through an orifice 4 in the casing 1, after being conducted thereto by suitable piping leading from the point or points at which the dust is produced.

30 5 is an air outlet in the forward end wall of the casing 1 that is surrounded by a suction pipe 6 that has associated with it a suction fan or any desirable means for producing a suction in said pipe (not shown).

35 7 designates a ring or tube located adjacent to the forward wall of the casing 1 and interior of said casing in a position to surround the air outlet 5.

40 8 is a ring or tube located interior of the casing 1 and at the rear wall of said casing in alinement with the ring 7.

45 A is a series of screen members that are disposed between the rings 7 and 8. These screen members consist of frames that are covered with suitable sheets 9 of fabric, such as canvas, the frames preferably comprising central rectangular members 10 which are located in alinement with the rings to provide a continuous duct through all of said members centrally of the screen, arms 11 extending outwardly from the members 10, and a border 12. 10^a are central rectangular spacing members located between each pair of screens. The screens are preferably connected to each other by screws which unite the central members 10 and spacing members 10^a as shown in Fig. III and serve to af-

ford substantially air tight joints between the screen members.

The dust and dust laden air from which the dust is to be arrested are drawn into the dust receiving chamber 3 of the arrester, due to suction created in the suction pipe 6, as a consequence of which the air is drawn from said chamber through the screen material of the screen members A and the dust is prevented from following the course of the air by the screens, and gathers upon the outer surface of the screen members. During this process a partial vacuum is created interior of the screen members and within the dust receiving chamber and due to the existence of a large area of screening surfaces in the arrester this vacuum is maintained practically the same both interior and exterior of the screen members, as a consequence of which the suctional action within the arrester is prevented from drawing the dust through the screen members, requiring that it settle in the hopper 2 at the bottom of the dust receiving chamber. 13 is a valve at the lower end of said hopper that may be 75 opened for the discharge of the collected dust.

For the purpose of dislodging the dust that accumulates upon the exterior surface of the screen members A, I provide a jarring mechanism which consists of strips 14 attached to the central screen frame members 10 and extending longitudinally of the series of screens and hammers 15 that are pivotally connected at 16 to the central screen frame members. These hammers are operated through the medium of a suitably driven shaft 17 extending longitudinally of the screen members and provided with cams 18 that are adapted to engage the rear ends of the hammer arms, thereby causing the hammers to partake of a rise and fall motion and act with jarring effect upon the strips 14 and the screen members to which said strips are attached. This jarring mechanism is intended to be placed into operation only periodically during the service of the dust arrester.

In the rear wall of the casing 1 is an air inlet 19 adjacent to which is a valve box 20 that is provided with a cover-valve 21.

22 is a screw stem seated in the valve box and adapted to be operated to open the valve 21 and hold it in an open position when it is desired to admit air from the exterior of the dust arrester to the compartments 100 interior of the screen members for the purpose of lessening the degree of suction therein if such suction should at any time prove too strong in the operation of arresting the dust delivered into the dust receiving chamber. The valve box is preferably attached to a door 23 that is mounted in the rear wall of the casing 1 and normally held in closed position by a catch 24 (see Fig. IV).

It will be observed that due to the construction of

the screen members A, as described, wherein the sheets of fabric are attached to frames on which the sheets are stretched and which are arranged in series, the screen members are rendered bag shape to provide an air space within each member into which the air drawn by suction in the pipe 6 freely enters and circulates throughout the extent of the space in each screen member.

I claim:—

- 10 1. A dust arrester comprising a casing, providing a dust receiving chamber, formed with a dust inlet orifice at the bottom, an air inlet at the rear end of the casing, an air outlet at the forward end of the casing, a hopper beneath the casing, an interior rear ring surrounding the air inlet, an interior forward ring surrounding the air outlet, a suction pipe leading from the air outlet, and a series of screens supported between the rings, each screen consisting of a pair of central rectangular members spaced apart and in alignment with the rings, a border, converging arms extending from the rectangular members to the border and screen material covering the space between the rectangular members and the border.
- 15 2. A dust arrester comprising a casing, providing a dust receiving chamber formed with a dust inlet orifice at the bottom, an air inlet at the rear end of the casing, an air outlet at the forward end of the casing, a hopper beneath the casing, an interior rear ring surrounding the air inlet, an interior forward ring surrounding the air outlet, a suction pipe leading from the air outlet, a series of screens supported between the rings each screen consisting of a pair of central rectangular members spaced apart and in alignment with the rings, a border, converging arms extending from the rectangular members to the border, and screen material covering the space between the rectangular members and the border.
- 20 3. A dust arrester comprising a casing, providing a dust receiving chamber formed with a dust inlet orifice at the bottom, an air inlet at the rear end of the casing, an air outlet at the forward end of the casing, a hopper beneath the casing, an interior rear ring surrounding the air inlet, an interior forward ring surrounding the air outlet, a suction pipe leading from the air outlet, a series of screens supported between the rings each screen consisting of a pair of central rectangular members spaced apart and in alignment with the rings, a border, converging arms extending from the rectangular members to the border, and screen material covering the space between the rectangular members and the border, and central rectangular spacing members between the screens.
- 25 4. A dust arrester comprising a casing, providing a dust receiving chamber formed with a dust inlet orifice at the bottom, an air inlet at the rear end of the casing, an air outlet at the forward end of the casing, a hopper beneath the casing, an interior rear ring surrounding the air inlet, an interior forward ring surrounding the air outlet, a suction pipe leading from the air outlet, a series of screens supported between the rings each screen consisting of a pair of central rectangular members spaced apart and in alignment with the rings, a border, converging arms extending from the rectangular members to the border, and screen material covering the space between the rectangular members and the border, a valve box adjacent to the air inlet having a cover-valve, and an adjustable screw stem adapted to work through the bottom of the valve box and against the cover-valve for controlling the latter.
- 30 5. A dust arrester comprising a casing, providing a dust receiving chamber formed with a dust inlet orifice at the bottom, an air inlet at the rear end of the casing, an air outlet at the forward end of the casing, a hopper beneath the casing, an interior rear ring surrounding the air inlet, an interior forward ring surrounding the air outlet, a suction pipe leading from the air outlet, a series of screens supported between the rings each screen consisting of a pair of central rectangular members spaced apart and in alignment with the rings, a border, converging arms extending from the rectangular members to the border, and screen material covering the space between the rectangular members and the border, a door hinged to the casing at the air inlet, a valve-box having a cover-valve and mounted in the door, and an adjustable screw-stem adapted to work through the bottom of the valve-box and against the cover-valve for controlling the latter.
- 35 6. A dust arrester comprising a casing, providing a dust receiving chamber formed with a dust inlet orifice at the bottom, an air inlet at the rear end of the casing, an air outlet at the forward end of the casing, a hopper beneath the casing, an interior rear ring surrounding the air inlet, an interior forward ring surrounding the air outlet, a suction pipe leading from the air outlet, a series of screens supported between the rings each screen consisting of a pair of central rectangular members spaced apart and in alignment with the rings, a border, converging arms extending from the rectangular members to the border, and screen material covering the space between the rectangular members and the border.
- 40 7. A dust arrester comprising a casing, providing a dust receiving chamber formed with a dust inlet orifice at the bottom, an air inlet at the rear end of the casing, an air outlet at the forward end of the casing, a hopper beneath the casing, an interior rear ring surrounding the air inlet, an interior forward ring surrounding the air outlet, a suction pipe leading from the air outlet, a series of screens supported between the rings each screen consisting of a pair of central rectangular members spaced apart and in alignment with the rings, a border, converging arms extending from the rectangular members to the border, and screen material covering the space between the rectangular members and the border.
- 45 8. A dust arrester comprising a casing, providing a dust receiving chamber formed with a dust inlet orifice at the bottom, an air inlet at the rear end of the casing, an air outlet at the forward end of the casing, a hopper beneath the casing, an interior rear ring surrounding the air inlet, an interior forward ring surrounding the air outlet, a suction pipe leading from the air outlet, a series of screens supported between the rings each screen consisting of a pair of central rectangular members spaced apart and in alignment with the rings, a border, converging arms extending from the rectangular members to the border, and screen material covering the space between the rectangular members and the border.

alignment with the rings, a border, converging arms extending from the rectangular members to the border, and screen material covering the space between the rectangular members and the border, strips attached to the rectangular members and extending longitudinally of the series of screens, hammers pivoted between the paired rectangular members, and a driven shaft extending through the series of screens, and having cams adapted to engage the hammers.

4. A dust arrester comprising a casing, providing a dust receiving chamber formed with a dust inlet orifice at the bottom, an air inlet at the rear end of the casing, an air outlet at the forward end of the casing, a hopper beneath the casing, an interior rear ring surrounding the air inlet, an interior forward ring surrounding the air outlet, a suction pipe leading from the air outlet, a series of screens supported between the rings each screen consisting of a pair of central rectangular members spaced apart and in alignment with the rings, a border, converging arms extending from the rectangular members to the border, and screen material covering the space between the rectangular members and the border, a valve box adjacent to the air inlet having a cover-valve, and an adjustable screw stem adapted to work through the bottom of the valve box and against the cover-valve for controlling the latter.

5. A dust arrester comprising a casing, providing a dust receiving chamber formed with a dust inlet orifice at the bottom, an air inlet at the rear end of the casing, an air outlet at the forward end of the casing, a hopper beneath the casing, an interior rear ring surrounding the air inlet, an interior forward ring surrounding the air outlet, a suction pipe leading from the air outlet, a series of screens supported between the rings each screen consisting of a pair of central rectangular members spaced apart and in alignment with the rings, a border, converging arms extending from the rectangular members to the border, and screen material covering the space between the rectangular members and the border, a door hinged to the casing at the air inlet, a valve-box having a cover-valve and mounted in the door, and an adjustable screw-stem adapted to work through the bottom of the valve-box and against the cover-valve for controlling the latter.
